UNITED STATES PATENT OFFICE.

CYRUS M. STONER AND FREDERICK B. STONER, OF CONNELLSVILLE, PENNSYLVANIA.

VALVE FOR STEAM-PUMP ENGINES.

1,058,919.

Specification of Letters Patent. Patented Apr. 15, 1913.

Application filed October 26, 1909. Serial No. 524,608.

To all whom it may concern:

Be it known that we, CYRUS M. STONER and FREDERICK B. STONER, citizens of the United States, residing at Connellsville, in the county of Fayette and State of Pennsylvania, have invented a new and useful Improvement in Valves for Steam-Pump Engines, of which the following is a specification.

10 This invention relates to a valve for engines of steam pumps and the object of the invention is to do away with the auxiliary valve usually employed upon direct acting pump engines and also to prevent the engine running away should the pump run out 15 of water or through any accident lose its vacuum. Usually under such circumstances an engine pump would continue to run at an abnormal speed until stopped by an attendant or through the breakage of some part of 20 the engine.

In order to regulate the speed of the pump and to avoid damage to it by too high a speed it has been common to employ what is 25 known as a "cataract," being an extra cylinder placed in advance of the steam chest and containing oil in which worked a piston connected to the piston valve of the steam chest, oil being moved through a suitable port, commonly placed in the piston itself, from one side of said piston to the other, and by its presence acting as a check and holding down the speed of the piston valve and consequently of the engine itself. 30

35 This cataract has usually been an expensive part of the engine construction and one of the essential features of our invention is the supplying of simple means for preventing the engine from running away and regulating its speed.

With these various objects in view, our invention consists of the novel features of construction, combination and arrangement of parts hereinafter fully described, pointed out in the claims and shown in the accompanying drawings, in which,

Figure 1 is an end view of an engine cylinder partly broken away and showing our invention in side elevation. Fig. 2 is a longitudinal section through a valve casing and through a hollow piston adapted to work therein. Fig. 3 is a section on the line 3—3 of Fig. 2. Fig. 4 is an irregular vertical longitudinal section through the valve casing, the piston being shown in a different position from that in Fig. 2. Fig. 5 is a sec-

tion on the line 5—5 of Fig. 4. Fig. 6 is a vertical section through the valve casing, midway its ends. Fig. 7 is a side elevation of a pump engine with our valve casing applied thereto, and illustrating the manner of connecting the valve mechanism to the piston rod of the engine. Figs. 8 and 9 are detail sectional views taken at right angles to each other and through a stuffing box and supporting bracket for the stem of a piston valve. Fig. 10 is a plan view of a valve.

In these drawings, 1 represents a steam pump engine and 2 a cylindrical valve casing, which for convenience is preferably placed transversely upon the top of the engine cylinder. This valve casing comprises a suitable base 3, which is bolted to the engine cylinder and the said base is provided with three parallel transverse slots 4, 5 and 6, which register with suitable openings in the top of the engine cylinder and afford communication between said cylinder and the valve casing. A hand operated plug valve 7, which is longitudinally slotted throughout a portion of its length as shown at 8 extends through the slot 5 and when turned so as to bring the slot 8 of the plug into alignment with the slot 5 permits communication through the said slot 8 between the interior of the valve casing and the exhaust of the engine cylinder. But when turned to bring said slot 8 at right angles to the slot 5, the plug valve 7 will cut off said communication. In an intermediate position, the said plug 7 will regulate the extent of communication between the valve casing and the exhaust of the engine through the slot 5 as illustrated in Fig. 4. Within the valve casing 2 is slidably and rotatably mounted a piston valve 9, which piston is hollow and closed at both ends. The piston 9 is provided at one end with an operating stem 10 and upon one side is inwardly depressed thus forming a cavity 11 between the side of the piston and the inner wall of the valve casing, and upon what is normally the underside of said piston valve, said cavity being of sufficient length to bridge two of the slots, 4, 5 or 6 at one time, as shown in Figs. 2 and 4. Adjacent its ends the piston valve is circumferentially slotted as shown at 12, and 13, said slots registering respectively and alternately with the slots 4 and 6, the slot 12 registering with the slot 4 only when the slot 13 is out of alignment with the slot 6, shown in Fig. 2.

It will be noted that when the piston valve is in such position that the slot 12 registers with the slot 4, the cavity 11 bridges the slots 6 and 7. When the slot 13 is brought into communication with the slot 6, the slots 4 and 5 have communication through the cavity 11. The piston valve is also provided with slots 14, and 15 in circumferential alinement respectively with the slots 12 and 13, but said slots 14 and 15 are off-set with respect to each other, the extent of the off-set depending upon the amount of rotation to be allowed the piston valve. The piston valve is also provided with a longitudinally extending groove 16, which extends from the rear end of the valve, that is that end opposite the stem 10 to a point adjacent the longitudinal center of said piston valve, terminating however short of said central point. The piston valve is also provided with two similar grooves 17 and 18 extending from the front end of the valve, the said grooves being parallel to each other and upon opposite sides of the longitudinal line upon which the groove 16 is formed, but it will be understood that the grooves 17 and 18 do not overlap the groove 16. The casing 2 is provided with circumferential slots 19 and 20 with which the slots 14 and 15 of the piston are adapted to register respectively. The slots 19 and 20 open into a steam space 21, which extends about half way around one side and the top of the valve casing. This steam space communicates with the grooves 16 and 17 in the piston valve by means of steam inlets 22 and 22^a, respectively. Exhaust ports 23 and 23^a are also adapted to be brought into communication by partial rotation of the piston, with said grooves, as will be explained more fully hereafter. Upon the side of the valve casing opposite the enlargement which forms the steam space 21 is a semi-cylindrical vertical enlargement 24. This is provided with a vertical bore 25, the upper end portion of which is enlarged to receive a vertically arranged plug valve 26. This plug valve is provided with a T-shaped bore thereby forming a horizontal passage 27 through the valve and a communicating vertical and downwardly open passage 27^a. The horizontal passage 27 communicates at its ends with the exhaust openings 23 and 23^a, which are angled for this purpose, as indicated in Fig. 5 and said exhaust ports being formed in the valve casing upon opposite sides of the vertical enlargement 24. The passage 27^a, opens downwardly into the bore 25 and said bore is adapted to communicate with the slot 8 through a transverse opening 8^a formed in the plug 7. The said plug 7 is provided with a hand operated lever 28, and the plug 26 is provided with a hand operated stem 29. Steam is delivered to the steam space 21 through a supply pipe 30.

In order to impart sliding movement to the valve 9 the stem 10 which works through a suitable stuffing gland 31 is provided with a squared portion 10^a upon which is mounted a handle 32 having a sleeve 33 journaled to 70 rotate in the bracket or bearing 34 carried by the gland 31, and to the outer end of said handle 32 is connected a link 35, which is loosely connected to one end of a pivoted arm 36, which in turn is pivotally connected 75 to a cross head 37 of the engine piston 38.

From the above description of the construction, it is believed that the following brief outline of the operation of these parts will be clear.

With the piston valve in the position shown in Fig. 4 steam will enter through the inlet 22^a and pass along the groove 16 into the rear end of the valve casing and by expanding therein will cause the piston valve 9 to 80 move forwardly. During such forward movement the piston valve is given a partial rotation by means of the arm 36, the link 35 and the valve handle 32. This rotation brings the groove 16 into registry with the 85 exhaust port 23^a, and at the same time places the groove 17 into communication with the forward steam inlet 22, and steam is therefore admitted to the front end of the valve casing through the groove 17. This causes 90 the piston to travel back and upon this rearward movement its rotation is reversed and the groove 18 is brought into registry with the exhaust port 23 and at the same time the groove 16 is again caused to register with the 95 inlet port 22^a. This operation will therefore continue indefinitely, the piston valve being given upon each stroke a partial rotation of about one and one-eighth inches.

As the piston valve is hollow, steam from 105 the space 21 will pass into the same through the slots 19 and 20 in the valve casing as the rotation of the piston valve brings the bores 14 and 15 into proper alinement with said slots. When the port 15 is in alinement 110 with the slot 20 as shown in Fig. 4 steam will pass from the space 21 directly to the engine through port 13 and the slot 6. When the piston valve is shifted to bring the part 14 into registry with the slot 19 the 115 port 12 will be brought into communication with the slot 4 and steam will pass to the engine cylinder through said slot. When the ports are in the position shown in Fig. 4 the exhaust is through slot 4, through the cavity 11 formed by the depression in the piston valve and by way of the slot 5 and plug 8. It will therefore be noted that the sliding movement of the piston valve not only connects alternately the ports 4 and 6 with the exhaust passage 5 but also through the combined sliding and rotary movement of the piston valve the steam employed in driving said piston valve back and forth is 125 also exhausted through slot 8 of the plug 7 130

which forms a common exhaust for both the valve casing and the engine. It will therefore be observed that the control of the exhaust from both the valve casing and from the engine is regulated by the plug valve 7. Furthermore, the exhaust from the valve casing can also be regulated by the valve 26. By means of these two valves the speed of the piston valve 9 is regulated and consequently the speed of the engine and we have found by experience that with the engine run up to three hundred pounds pressure and the suction pipe then pulled out of the water the engine would only run three strokes per minute faster than its normally running speed.

What we claim is:

1. The combination with an engine pump, having steam inlet passages and an exhaust passage arranged between the said inlet passages, of a valve casing arranged transversely upon said pump and communicating with said passages, a hollow piston valve working in said valve casing and pressed inwardly to form a cavity adapted to bridge at the same time the exhaust passage and a steam inlet of the engine, means for admitting steam into opposite ends of said valve casing, means for giving a partial rotation to the valve piston, the valve casing being provided with a valve controlled exhaust pas-

sage, a slotted plug valve rotatably mounted to control the exhaust passage of the engine, the exhaust passage of the valve casing communicating with the slot of said plug valve, 35 the piston valve being slotted and longitudinally grooved, as and for the purpose set forth.

2. In combination with a pump engine, a valve casing mounted thereon, a slidable and rotatable valve working in said casing, said valve being hollow provided with suitable openings in its sides, and longitudinally grooved upon its exterior the valve casing being provided with ports and slots adapted to register with the grooves and openings in the piston valve, the said piston valve in its sliding movement controlling the admission of steam to and exhaust from the engine, steam for moving said valve passing 50 to and exhausting from the ends of the valve casing through said grooves, the said valve casing being provided with a valve controlled exhaust communicating with the exhaust passage of the engine pump, and 55 means for giving a partial rotation of the piston valve once during each stroke.
